7 Claims

ABSTRACT OF THE DISCLOSURE

Decoked alkaline sulfite pulp liquor having an excess of soluble sulfite ion is regenerated by treating with an alkaline earth oxide and/or hydroxide to precipitate excess soluble sulfite ion as insoluble alkaline earth sulfite. The sulfite precipitate is removed by filtration and the resulting liquor is recycled to the pulping operation. The alkaline earth oxide and SO₂ are recovered from the filter cake by heating.

FIELD OF THE INVENTION

This invention relates to a process for regenerating decoded alkaline sulfite pulp liquor from acid coking operation by treating with an alkaline earth oxide or hydroxide.

BACKGROUND OF THE INVENTION

A process for coking waste alkaline sulfite liquor disclosed in commonly assigned copending application Ser. No. 149,425, filed even day herewith, is characterized by the step of acidifying the liquor with SO₂ in order to facilitate the coking as evidenced by being able to coke the lignins faster and at a lower temperature. The coke-free liquor resulting from the process contains valuable dissolved chemicals, the recycling of which to the pulping operation would enhance the economics of the whole process. This liquor however is acid and the alkaline sulfite wood pulping process desirably must be carried out at a pH of 9 to 12. An obvious way to render the decoded liquor suitable for reuse in the sulfite wood pulping process is to add enough sodium hydroxide thereto but this approach undesirably results in the build-up of both sodium hydroxide and sulfur as sulfite in the wood pulping system.

SUMMARY OF THE INVENTION

It has now been discovered that decoded acid sulfite liquor may be regenerated by treatment with an alkaline earth oxide or hydroxide (the oxide or hydroxide of calcium being preferred) to precipitate the sulfite contained therein and to regenerate NaOH according to the following equation:

Filtration removes the CaSO₃ · 2H₂O and the resulting liquor is recycled to the pulping operation. Unslaked lime and SO₂ are recovered from the filter cake by dewatering and calcining in the presence of air to a temperature above 1200° F. but preferably in the range of 1500–2000° F., thus:

2

Heating CaSO₃ at a reduced temperature of 950° to 1200° F. will result in the following disproportionation:

However advantageously

- 10 The SO₂ is recycled to the coking step and the CaO is used in the treatment of the acid liquor in Equation 1.
The amount of alkaline earth oxide or hydroxide added to the acid decoded liquor will vary with the pH of this liquor. Generally, the amount will range from 5–50 grams
15 Ca(OH)₂ per liter of liquor in order to bring the liquor back to pH 7–12.
The use of Ca⁺⁺ ion is preferred to the use of Ba⁺⁺ or Mg⁺⁺ because the former is less expensive; however, mixtures of the ions may be used; e.g., Mg⁺⁺ and Ca⁺⁺.
20 The use of the calcium salt has the added advantage of lower solubility than either the salt of the other two alkaline earth metals, as indicated below:

Salt:	Solubility in 100 parts of cold water
CaSO ₃ · 2H ₂ O	0.0043
BaSO ₃	0.0197
MgSO ₃ · 6H ₂ O	1.25
Na ₂ SO ₃ · 7H ₂ O	34.7

- 30 The following examples are presented to illustrate more clearly the invention. The same, however, is not limited to these specific embodiments.
Example I shows the characteristics of a spent alkaline sulfite liquor and Example II shows the acidification of this spent liquor by the adsorption of SO₂. In Example III, the acid liquor from Example II was coked in the liquid phase to effect an 86% reduction in Total Organic Carbon in the liquid (filtrate). The washed and dry filter cake recovered has a low sodium content but a substantial sulfur content and heat of combustion. The cake can be advantageously burned for the recovery of heat and chemicals. The filtrate containing the bulk of the chemicals is acid, pH 4.4, and needs to be brought to the alkaline side prior to recycle.
45 Example IV shows that this was done by treating with slaked lime, thereby converting the liquor to a pH of 11.8 and removing excess SO₃⁼ ion, e.g.,

- 50 The CaSO₃ was removed by filtration and heated to regenerate chemicals, thus:

- Example V shows that the recovered filtrate, even without refortifying was effective in removing substantial quantities of the lignins from pine wood chips.

Ba(OH)₂ was the alkaline earth hydroxide used in Example VI to effect regeneration of the acid filtrate of Example III. A liquor having a pH of 11.9 was obtained.

60 Example VII shows that Mg(OH)₂ was equally effective in altering the pH of Example III decoded waste liquor.

Sulfites are sensitive to oxidation by free oxygen to sulfates. Sulfates are an undesirable product in the process so care is exercised in the handling of the process liquid and alkaline metal sulfite to avoid contact with air.

EXAMPLE I

A waste alkaline sulfite liquor gave the following analysis:

Sample number	1
Sulfur, wt. percent	1.59
Sodium, wt. percent	3.6
Calcium, wt. percent	0.05
Nitrogen, wt. percent	0.007
TOC, wt. percent ¹	5.6
Ash, wt. percent	9.46
Dissolved solids, wt. percent	19.8
COD, g./l.	156.5
pH	11.9

¹ Total organic carbon.

Example II

1000 parts by weight of Sample 1 alkaline sulfite liquor, were placed in a vessel and SO_2 was slowly bubbled into the liquor. A total of 117 parts by weight of SO_2 were absorbed. The liquor's pH now was 1.9 (Sample 2).

Example III

500 parts by weight of the Example II liquid (Sample 2) were placed in an autoclave. The autoclave was flushed with nitrogen and sealed. The autoclave was then heated to 552° F., and held at this temperature for two hours. A pressure of 1200 p.s.i.g. was generated. The autoclave was cooled to 80° F. and vented. A total of 3.8 parts by weight of gas was recovered (Sample 6). A total of 449 parts by weight of liquids and solids were recovered. Filtration yielded 378 parts by weight of light yellow liquid (Sample 3) and 68 parts by weight of wet filter cake. 34 parts by weight of the filter cake were dried on a steamplate to give 14.3 parts of dry cake (Sample 4). The outer 34 parts by weight portion of the filter cake were washed with 1000 parts of water and after drying on steamplate, 12.6 parts by weight of dry cake (Sample 5) were secured.

Tests on the filtrate are as follows:

Sample:	Filtrate
Sample No.	3
Sulfur, wt. percent	2.7
Sodium, wt. percent	3.7
Calcium, wt. percent	0.05
Nitrogen, wt. percent	0.002
TOC, wt. percent	0.8
Ash, wt. percent	12.6
Dissolved solids, wt. percent	12.9
COD, g./l.	28.1
pH	4.4; 4.5

Analysis of the filter cakes gave the following:

Sample	Unwashed dry cake	Washed dry cake
Sample number	4	5
Sulfur, wt. percent	23.3	31.2
Sodium, wt. percent	4.3	0.2
Ash, wt. percent	33.8	16.5
Gross heat of combustion, B.T.U./lb.	6,988	8,863

Tests on the gas stream from coking are as follows:

Sample No.	6
Thiophene	mole percent
Dimethyl sulfide	do
Methyl mercaptan	do
CO_2	do
H_2S	do
H_2	do
$\text{C}_1\text{-C}_2$	do

Example IV

100 parts by weight of filtrate from Example III (Sample 3) reacted with 3.0 parts by weight slaked lime, $\text{Ca}(\text{OH})_2$, at room temperature. A precipitate formed that was filtered from the solution. 94.5 parts by volume

of filtrate was collected (Sample 7) and 6.5 grams of filter cake. The latter contained 57 percent moisture.

Sample	Filtrate	Dry filter cake
Sample number	7	8
Sulfur, wt. percent	2.14	8.06
Sodium, wt. percent	3.72	1.14
COD, g./l.	19.9	-----
pH	11.8	-----

10 The filter cake was placed in a glazed ceramic vessel and heated to red heat. During the heating process acid vapors were noted that were identified as SO_2 . Ash, representing 95% of the charge was recovered, and identified as Sample 9. Sample 9 has 10.7 weight percent of sulfur.

Example V

15 10 parts by weight pine wood chips were steamed in an autoclave at 350° F. and 125 p.s.i.g. pressure for 15 minutes, cooled and allowed to drain to remove any excess water. 50 parts by volume of filtrate (Sample 7) from Example IV was added to the steamed wood chips contained in the autoclave. The autoclave was then heated to 340–350° F., the wood chips allowed to digest at this temperature for 90 minutes; cooled and the pulp was withdrawn from the digester. The pulp was washed and dried to recover 7.4 parts by weight of dry paper pulp (i.e., equal to 26 weight percent loss of lignins) and 49 parts by weight of liquid having a dark brownish color (Sample 10). Sample 10 had a pH of 6 and a COD of 4430 mg. O_2 /l.

Example VI

20 25 parts by weight of filtrate from Example III (Sample 3) was reacted with 3.5 parts by weight of $\text{Ba}(\text{OH})_2$ at room temperature. The reacted product was filtered to give 23.2 parts by volume of filtrate and 5.0 parts by weight of wet filter cake. The latter contained 63.5 percent moisture.

Sample	Filtrate	Dry filter cake
Sample number	11	12
Barium, wt. percent	-----	53.5
Sulfur, wt. percent	2.00	3.9
Sodium, wt. percent	3.91	2.26
COD, g./l.	18.4	-----
pH	11.9	-----

25 A portion of the wet filter cake was placed in a glazed ceramic vessel and quickly heated to a red heat. During the heating process acid vapors were noted that were identified as SO_2 . 0.366 parts by weight of ash (Sample 13) was recovered. This represented 17.2 percent of the wet cake. Tests on the ash (Sample 13) are as follows:

	Wt. percent
Sulfur	4.7
Barium	53.9
Sodium	2.2

Example VII

30 25 parts by volume of filtrate from Example III (Sample 3) was reacted with 1.5 grams $\text{Mg}(\text{OH})_2$ at room temperature. The reacted product was filtered to give 23.6 parts by weight of filtrate (Sample 14) and 2.8 parts by weight of wet filter cake. The latter contained 52 percent moisture.

Sample	Filtrate	Dry filter cake
Sample number	14	15
Sulfur, wt. percent	2.67	10.1
Sodium, wt. percent	3.82	5.3
COD, g./l.	11.3	-----
pH	11.9	-----

35 A portion of the wet filter cake was placed in a glazed ceramic vessel and heated rapidly to a red heat. During the heating process acid vapors were noted that were

identified as SO_2 . 0.4005 parts by weight of ash (Sample 16) was recovered. This represented 14.3 weight percent of the wet cake. Tests on the ash (Sample 16) are as follows:

	Wt. percent	5
Sulfur	9.3	
Sodium	5.2	

What is claimed is:

1. In a process for the regeneration of pulp liquor wherein the liquor is acidified with SO_2 , coked to produce an alkaline sulfite pulp liquor and coke, and the alkaline sulfite pulp liquor and coke are separated, the steps of: treating the acidified, separated liquor with an amount of alkaline earth metal oxide or hydroxide sufficient to bring the pH of said liquor to between about 7 and 12, and to form an alkaline earth metal sulfite separating the alkaline earth metal sulfite from said liquor, recycling said liquor to pulping operation, and heating said alkaline earth metal sulfite to about 1200° F. to form the corresponding alkaline earth metal oxide and sulfur dioxide, said steps being carried out substantially in the absence of air to avoid oxidation of sulfites to sulfates.

2. The process according to claim 1 wherein said alkaline earth metal sulfite is heated to a temperature of between about 1200° F. and 2000° F.

3. The process according to claim 1 wherein said alka-

line earth metal oxide obtained by heating said sulfite is used in treating said liquor.

4. The process according to claim 1 wherein said alkaline earth metal oxide or hydroxide is calcium oxide or hydroxide.

5. The process according to claim 1 wherein said alkaline earth metal oxide or hydroxide is barium or magnesium oxide or hydroxide.

6. The process according to claim 1 wherein there are used from 5 to 50 grams of calcium hydroxide per liter of liquor.

7. The process according to claim 1 wherein a mixture of alkaline earth metal oxides or hydroxide is used to treat the liquor.
